UNITED STATES PATENT OFFICE.

ALBERT S. WHEELBARGER, OF DAYTON, OHIO, ASSIGNOR TO OHMER FARE REGISTER COMPANY, OF DAYTON, OHIO, A CORPORATION OF NEW YORK.

PAPER-TAKE-UP MECHANISM.

Application filed January 17, 1927. Serial No. 161,638.

The object of this invention is to provide a paper takeup mechanism so as to keep the paper fed from a supply roller in a taut condition. While the device is capable of being used everywhere paper is unwound from a supply roller, it was primarily designed to retain the ticket and record strips of paper shown in my co-pending applications 53,082, filed August 28, 1925, and 65,532, filed 10 October 29, 1925, in a taut condition. In these applications ticket and record supply rollers are shown but difficulty has been experienced on account of the paper becoming slack. This was occasioned because of the fact that when 15 the paper was originally inserted it probably was not properly tensioned. Ordinary feeding methods heretofore known did not take up this surplus paper. The present invention overcomes this objection.

Another object of the invention is to provide a mechanism which while keeping the paper taut will permit a certain amount to be readily unwound from the supply rollers, for instance, when the paper is being inserted 25 in the machine, but thereafter will take up the surplus paper.

While I have mentioned that the invention was primarily designed to overcome an objection existing in the machines shown in my 30 previous applications, it is readily apparent that the invention is capable of being used in cash registers, adding machines, and for a multitude of other purposes. I have, by way of illustration, shown the invention in connection with a type of machine similar to that shown in my previous applications.

Referring more particularly to the drawings:

Fig. 1 is a plan view of a part of the printing mechanism having my invention incorporated therein.

Fig. 2 is a cross-sectional view on the line 2—2 of Fig. 1, looking in the direction of the arrows.

Fig. 3 is an elevational view of the right side of the machine shown in Fig. 1.

Fig. 4 is a cross-sectional view on the line 4—4 of Fig. 2.

Fig. 5 is a cross-sectional view on the line 5—5 of Fig. 2.

Fig. 6 is an elevational view on the line 6—6 of Fig. 4 looking in the direction of the arrow.

Fig. 7 is an elevational view on the line 7—7 of Fig. 4.

Fig. 8 is a detailed view of the takeup mechanism shown in Fig. 3, and

Fig. 9 is a cross-sectional view on the line 9—9 of Fig. 3.

A main actuating shaft 1 is provided with two disks 2 connected to pitmen 3 which are operatively connected to a shaft 4 which carries the platen 5 which presses the strip of paper 6 against the printing disks 7. The shaft 4 is mounted on arms 8 pivoted on collars 10 and 11. The shaft 4 also carries an arm 13 having a lug 14 connected to a spring 12 secured to an arm 8 by means of a pin 15, which arm 13 carries an inking roller 16 and a guard 17, which guard prevents the paper from coming into contact with the inking roller 16.

One of the arms 8 is provided with an extension 18 which carries a pin 19 which pin engages a slotted member 20 connected to a pivoted arm 21, which carries a double-nosed dog 22, which dog engages a ratchet 23 secured to a shaft 24 which shaft is provided with a knob 25 by which the shaft may be rotated manually if necessary. The dog 22 is provided with a slot 26 which receives the pin 27 carried by the pivoted arm 21. A pin 28 is carried near the upper end of the dog 22 and the spring 29 interposed between the pins 27 and 28. The spring 29 performs the function of causing the dog 22 to always engage the teeth of the ratchet 23.

The slotted member 20 is provided with a pin 30 to which is secured a spring 31 having its other end secured to the shaft 4, the object of the spring 31 being to hold the member 20 against the pin 19. The member 20 is provided with a slot 32 in which slides a pin 33 carried by a bell crank lever 34 fulcrumed on the shaft 35, the arm 36 of the lever 34 carrying a roller 37 which engages takeup roll 38. The takeup roll 38 is mounted on a shaft 39 which shaft is journaled in the shaft 24 and in one of the sidewalls 40 of the machine. The shaft 39 is provided with a slot 45 95 100

41 which received a J-shaped rod 42, between which and the shaft 39 the paper is anchored. The end 43 of the rod 42 which rests against the disk 43^a carried by the shaft 39 also provides a connection between the shaft 39 and the shaft 24 by fitting into a slot 44 in the inner end of the shaft 24. The supply roll of paper 45 is mounted on the shaft 9, which shaft carries a disk 46 slidably 10 mounted on the shaft 9, but being held against rotative movement thereon by flat sides 47 of the shaft 9, the disk 46 being provided with a similarly shaped aperture. A spring spider 48 is rigidly secured to the 15 outer end of the shaft 9 and presses the disk 46 inwardly. The other end of the shaft 9 is provided with a screw-threaded aperture 49 which receives a threaded shaft 50 which carries a disk 51. By this threaded connection the distance between the disks 46 and 51 may be adjusted. The member 50 also carries a projection 52 seated in a slot 53 in the 20 slidable member 54, which member 54 is provided with a knob 55 which may be engaged by the hand of the operator to pull the member 54 against the tension of the spring 56 so that the shaft 9 may be removed. The other end of the shaft 9 is provided with a 25 projection 52 received in the slot 53 in the shaft 57 which shaft carries a disk 58 provided with a pin 59 which engages one of the arms of the spider 48. A collar 60 surrounds the shaft 57, and around the collar 60 is a helical spring 61 anchored in the disk 58 at 30 62 and attached to a pin 63 on a stationary collar 64 secured to the collar 60. The shaft 57 is also provided with a disk 65 which disk 35 carries a lug 66, the disk and lug being provided with aligned valleys 67 capable of receiving a gear tooth. The lug 66 is of a width equal to two gear teeth. The valley in the lug 66 in effect forms two teeth. A pinion 68 is mounted on a stud shaft 69, all 40 of the teeth except three of the pinion being double the width of the disk 65 or the combined width of the disk 65 and lug 66. These long teeth are denoted by the reference character 70 while the three short teeth which engage the valley 67 in the lug 66 are denoted 45 by the reference character 71. The three short teeth alternate with the long teeth.

When it is desired to insert a new roll of paper 45, the knob 55 is pulled outwardly so that the shaft 9 and disks 46 and 51 can be 55 removed. A threaded screw 50 is unscrewed from the shaft 9 by simply rotating the disk 51. The paper can now be slipped over the shaft 9 until it comes into position against the disk 46. The screw 50 may now be 60 screwed into the hole 49 bringing the disk 51 against the other end of the roll of paper. A slight further rotation of the disk 51 will cause the paper to be pushed against the disk 46 against the tension of the spider 48, so 65 that there will be more or less friction be-

tween the disks 46 and 51 and the roll 45 as the paper is unwound while the disks are held stationary. The disks are, however, permitted to rotate for a predetermined distance. This free rotation is advisable because as the paper is inserted on the shaft 9 it is necessary to train the paper over the platen and onto the takeup roll as shown in Fig. 2. After inserting the roll 45 on the shaft 9 and when the paper is thereafter pulled, one of the arms of the spider 48 engages the pin 59 which rotates the disk 58 and tensions the spring 61 in much the same manner as the spring in a window-shade is tensioned. As the disk 58 rotates the disk 65 is likewise rotated in the direction of the arrows shown in Fig. 8. After rotating one complete revolution, the two teeth on the lug 66 engage one of the long teeth 70 of the pinion 68 rotating it one tooth, the periphery of the disk 65 thereafter passing between the end of one of the short teeth 71 and the sidewall 40, the two adjacent long teeth 70 engaging the periphery of the disk 65 and locking it against further rotation. When the disk 65 makes a second and a third revolution this action is repeated but as there are only three short teeth 71 additional rotations of the disk 65 are rendered impossible. The spring 61 has therefore been tensioned by the action of three revolutions of the roll 45 or of the disk 65. By this time the paper will be in a taut condition and will thereafter be unwound from the roll 45 against the friction existing between the disks 46 and 51 and the roll 45. This friction is not sufficiently strong to tear the paper but is sufficiently strong to maintain substantial friction between the disks and the roll. As before mentioned the amount of this friction can be adjusted by adjusting the screw 50.

While I have shown as a preferred construction the pinion 68 as being provided with three short teeth, it is obvious that this number may be varied so as to permit the roll 45 to rotate with the disk 65 for any given number of revolutions, depending altogether upon what degree of tension it was desired to impart to the spring 61. It is also obvious that many other variations may be made from the specific form shown by way of illustration and I, therefore, desire to claim my invention broadly regardless of the modifications which may be made therein, provided such modifications fall within the scope and the broad meaning of the appended claims.

Having described my invention, I claim—

1. In a tensioning device, means whereby resistance is offered to the unrolling of a roll of paper for a predetermined number of revolutions thereof, and means thereafter offering a greater resistance to such unrolling.

2. In a tensioning device, means whereby an increasing resistance is offered to the un-

rolling of a roll of paper for a predetermined number of revolutions thereof, and means thereafter offering a greater resistance to such unrolling.

5. 3. In a tensioning device, a shaft, a roll of paper thereon, means whereby resistance is offered to the unrolling of the roll of paper while a predetermined amount of said paper is being unwound, and means thereafter locking said shaft against rotation while permitting said roll to rotate relative to said shaft.

4. In a tensioning device, means whereby increasing resistance is offered to the unrolling of a roll of paper for a predetermined number of revolutions thereof, and means immediately effective after said predetermined number of revolutions offering a greater resistance to such unrolling.

5. In a tensioning device, a shaft, a roll of paper thereon, spring means whereby increasing resistance is offered to the unrolling of the roll of paper while a predetermined amount of paper is being unwound, means whereby said shaft is then locked against rotation and friction means thereafter offering a greater resistance to such unrolling while permitting said roll to rotate relative to said shaft.

6. In a tensioning device, a shaft on which a roll of paper is mounted, means whereby resistance is offered to the rotation of said shaft for a predetermined number of revolutions, and means to lock said shaft against rotation after said given number of revolutions while permitting said roll to rotate relative to said shaft.

7. In a tensioning device, a shaft on which a roll of paper is mounted, means whereby resistance is offered to the rotation of said shaft for a predetermined number of revolutions, means to lock said shaft against rotation after said given number of revolutions, and means to frictionally engage said roll when said shaft is locked.

8. In a tensioning device, a shaft on which a roll of paper is mounted, means whereby resistance is offered to the rotation of said shaft for a predetermined number of revolutions, means to lock said shaft against rotation after said given number of revolutions, means to frictionally engage said roll when said shaft is locked, and means to adjust the amount of friction between said means and said roll.

9. In a tensioning device, a shaft, disks on said shaft adapted to resiliently engage a roll of paper, means whereby resistance is offered to the rotation of said shaft and disks for a predetermined number of revolutions, and means to lock said shaft against rotation after said given number of revolutions.

10. In a tensioning device, a shaft, disks on said shaft adapted to resiliently engage a roll of paper, means whereby resistance is

offered to the rotation of said shaft and 65 disks for a predetermined number of revolutions, means to lock said shaft against rotation after said given number of revolutions, and means to adjust said disks relative to said roll.

11. In a tensioning device, a shaft on which a roll of paper is mounted, disks on said shaft adapted to resiliently engage said roll of paper, means to press one of said disks against the paper, means whereby resistance 75 is offered to the rotation of said disks and shaft for a predetermined number of revolutions, and means to lock said shaft against rotation after said given number of revolutions.

12. In a tensioning device, a shaft on which a roll of paper is mounted, disks on said shaft adapted to resiliently engage said roll of paper, means to press one of said disks against the paper, means whereby resistance is offered 85 to the rotation of said disks and shaft for a predetermined number of revolutions, and spring means to lock said shaft against rotation after said given number of revolutions.

13. In a tensioning device, a shaft, disks 90 on said shaft adapted to resiliently engage a roll of paper, one of said disks being slidably mounted on said shaft, a spider on said shaft adapted to press said slideable disk against said roll, a spring, and means whereby said spider tensions said spring as said shaft is rotated.

14. In a tensioning device, a shaft, disks on said shaft adapted to resiliently engage 100 a roll of paper, one of said disks being slidably mounted on said shaft, a spider on said shaft adapted to press said slideable disk against said roll, a spring, means whereby said spider tensions said spring as said shaft is rotated, and means to prevent the rotation 105 of said shaft after it has been rotated to a predetermined extent.

15. In a tensioning device, a shaft, a spring operatively connected to said shaft so that 110 said spring will be placed under tension as said shaft is rotated, and means to lock said shaft against further rotation after it has been revolved to a predetermined extent.

16. In a tensioning device, a shaft, a spring operatively connected to said shaft so that 115 said spring will be placed under tension as said shaft is rotated, and means to lock said shaft against further rotation after it has been revolved to a predetermined extent, said means consisting of a notched disk and a 120 modified Geneva gear.

17. In a tensioning device, a shaft, a spring operatively connected to said shaft so that 125 said spring will be placed under tension as said shaft is rotated, and means to lock said shaft against further rotation after it has been revolved to a predetermined extent, said means consisting of a pinion hav-

ing a plurality of wide teeth and a certain number of teeth of reduced width, a disk provided with a notch adapted to receive one of the wide teeth, a lug on said disk provided with a notch adapted to receive one of the teeth of reduced width, said wide teeth engaging the periphery of said disk locking

said pinion against rotation until said lug receives one of said teeth of reduced width, the number of wide teeth being limited so as to prevent the rotation of said disk after a predetermined number of revolutions.

In testimony whereof I affix my signature.

ALBERT S. WHEELBARGER.
